OR D11,758 EX

No. 11,758

May 4, 1880

UNITED STATES PATENT OFFICE.

RODOLPHE CHRISTESEN, OF NEW BRITAIN, CONNECTICUT, ASSIGNOR TO
THE RUSSELL & ERWIN MANUFACTURING COMPANY, OF SAME PLACE.

DESIGN FOR HINGES.

SPECIFICATION forming part of Design No. 11,758, dated May 4, 1880.

Application filed April 3, 1880. Term of patent 14 years.

To all whom it may concern:

Be it known that I, RODOLPHE CHRISTESEN, of the city of New Britain, and county of Hartford and State of Connecticut, have invented a new and useful Design for Door Hinges; and I do hereby declare that the following specification, taken in connection with the accompanying photographic illustration, forming a part of the same, is a full, clear, and exact description thereof.

The design hereinafter described is adapted to the wings of a door-hinge, and possesses, in addition to the specific ornamentation, the following novel characteristics: The ornamentation of one wing differs in detail from that of its fellow wing, and upon each is a portion of a connecting element which joins the two separate ornamentations into a harmonious pictorial design whose central portion is obscured by the knuckle of the hinge, which is apparently located between the eye of the observer and the design as a whole, and forms no part thereof.

The specific ornamentation chosen to illustrate this novel feature in designs for door-hinges is in the Egyptian style, and is composed as follows:

Referring to the accompanying illustration, A A' represent the two wings of the hinge, and B the knuckle, which may be plain or ornamented, as desired. The upper portion of each wing is ornamented by a frieze border, a a', which is apparently supported by columns b b', one on each wing. The lower portion of each wing is ornamented by a dado border, c c', which is apparently in the rear of the columns b b' and the knuckle B, and supports a

column, d, on the wing A. Surmounting the border c c' is a figure, C, representing a winged centaur, whose anterior portion is upon the wing A and posterior portion upon the wing A', the central portion of the figure being obscured or hidden by the knuckle B. The figure C, therefore, forms a connecting-link between the respective ornamentations of the wings and joins them into a harmonious design.

The remaining ornamentation consists of a pedestal and urn, d', upon the wing A' and a column showing partly on both wings and located in the extreme background in the rear of both knuckle B and figure C.

It is to be understood that the design above described is chosen to illustrate the novel feature in designs for door-hinges, which feature consists in ornamenting the respective wings with differing details, and employing an element which is partially obscured by the knuckle, is located partly on both wings, and joins the ornamentation upon the respective wings into one harmonious design.

What I claim, and desire to secure by Letters Patent, is—

The design for hinges, substantially as shown and described, embodying differing ornamentations on the respective wings and an element partially located on both wings, partly obscured by the knuckle, joining the respective ornamentations into a harmonious design, and forming a component part of the whole design.

RODOLPHE CHRISTESEN.
